UNITED STATES PATENT OFFICE.

ADAM B. FAHNESTOCK, OF MANHASSET, NEW YORK, ASSIGNOR, BY MESNE ASSIGNMENTS, TO LOCOMOTIVE STOKER COMPANY, OF PITTSBURGH, PENNSYLVANIA, A CORPORATION OF PENNSYLVANIA.

MECHANICAL STOKER.

Original application filed September 21, 1923, Serial No. 664,132. Divided and this application filed September 16, 1924. Serial No. 737,999.

My invention relates to appliances for reducing coal to portions of suitable size for firing, while in transit from a supply receptacle to the firebox of a locomotive or other 5 steam boiler furnace, and its object is to provide an appliance of such type which shall be of strong and simple construction, and readily adaptable for operation on locomotives of present standard types, and in the 10 operation of which, lumps of dimensions in excess of requirements shall be crushed to proper size and delivered to the fire box with the portion of the supply of coal which is sufficiently fine to be used without reduction of size.

The improvement claimed is hereinafter fully set forth.

In the accompanying drawings: Figure 1 is a side view of a mechanism illustrating 20 an embodiment of my invention; Fig. 2, a vertical longitudinal central section through the same; Fig. 3, a plan view; and, Fig. 4, a transverse section, on the line *a a* of Fig. 2.

In the practice of my invention, referring 25 descriptively to the specific embodiment thereof which is herein exemplified, fuel is supplied to the crushing mechanism thereof, by any suitable and preferred fuel feeding mechanism, as, for example, the drag chain 30 mechanism set forth in my co-pending application for Letters Patent, Serial No. 664,132, of which application, this is a division, said mechanism comprehending a plurality of loops of endless drag chains, 2, 35 traversing longitudinally in a feeder trough, or channel, 1, supported on a frame, 1^a.

In the operation of stoker fired locomotives, it is frequently necessary to supply them with run of mine coal, which contains 40 lumps that are too large for proper combustion in the firebox, and it is manifestly desirable that they should be capable of using coal of such character, when desired. To this end, a coal crushing mechanism, of substantially the following construction, is 45 preferably provided.

A stationary crusher member, indicated, as a whole, as 21, is secured to the frame, 1^a, adjacent the forward ends of the feeding 50 drag chains, 2. The stationary crusher mem-

ber is a substantial casting, comprising a plurality of vertical longitudinal ribs, 21^a, having their forward ends facing towards a movable crusher member, and connected by upper transverse ribs, 21^b, and lower transverse ribs, 21^c. A shaft, 40, mounted in bearings in the frame, and carrying sprocket wheels, 4, over which the drag chains, 2, traverse, passes through openings in the side walls and ribs of the stationary crusher member, 55 and the chains pass through slots, 21^e, of approximately the same width as the chains, between the ribs 21^a, said slots being extended beyond the forward limit of traverse of the chains to leave free openings in the top 60 of the stationary crusher member. The openings at the front of the stationary member, at the rear of the upper transverse ribs, 21^b, and between the vertical ribs, 21^a, permit such particles of coal as are so small as 65 not to require crushing, to drop into the conveyor casing, 24^a, without being crushed.

It will be seen that the stationary crusher member is of open work or lattice form, its front face wall being formed with a plurality of approximately rectangular openings. Vertical rows of teeth, 21^f, project 70 from the front wall, between the openings thereof.

A movable crusher member, 22, of sectoral 75 form, is fixed on a shaft, 23, which is journaled in the supporting frame, 1^a, adjacent to its front end, said member having a plurality of sets of teeth, 22^a, which project rearwardly from its curved body, the sets 80 being disposed in parallel vertical planes, and the outer ends of the teeth in curves eccentric to the axial line of the shaft, 23. Rocking movement, about said axial line, is 85 imparted to the movable crusher member, by a connecting rod, 25, coupled, at one end, to a crank arm, 12^a, on a shaft, 12, journaled transversely in the frame, and, at the other, to a crank arm, 23^a, on the shaft, 23, of the 90 movable crusher member. The shaft, 12, is 95 rotated by any suitable prime mover (not shown) which rotates a shaft, 9^a, carrying a pinion, 10, engaging a spur gear, 11, on the shaft, 12. The shaft of a screw conveyor, 24, which operates in a casing, 24^a, and 100

serves for the delivery of coal from the crushing mechanism to the firebox of the boiler in which it is to be consumed, is also rotated by the shaft, 9^a, through a bevel pinion, 9^b, engaging a similar gear, 27^a, on a shaft, 27, connected, by an universal joint to the shaft of the conveyor, 24.

The eccentricity of the teeth of the movable crusher member, 22, relatively to its axis of movement causes them to approach the stationary member, in the movements of the movable member in the direction of the stationary member, and to recede from the stationary member, in the opposite direction of movement, so as to allow the preliminarily crushed lumps of coal to drop further into the space between the stationary and movable members. The lumps being supported by the ribs of the stationary member, are struck and broken by the higher projecting teeth of the movable member. The greater portion of the crushed coal, passes through the openings in the stationary member, thus having the effect of quickly freeing the mechanism from crushed material. Any coal remaining, which has not passed through the openings, is dropped into the delivery conveyor on the back stroke of the movable member.

In the operation of the mechanism herein exemplified, the continuous supply of coal from the coal bin on the tender of the locomotive, or other supply receptacle, to the conveyor by which it is delivered to the stoking mechanism on the locomotive, is effected by the forward movements of the upper lengths of the drag chains, the quantity of coal delivered being proportionate to variation in the extent of their intermittent movements, which may be regulated, from time to time as desired, by the operator. The larger lumps of coal are, as before described, crushed in passing between the stationary and movable crushing members, and, together with the smaller particles, drop into the conveyor casing, and are carried, by the delivery conveyor, to the stoking appliance proper.

The relative disposition of the feeder chains and the crushing members is of substantial advantage in providing a structure in which said members are disposed entirely beyond the traverse of the feeder chains, which are thereby completely exempted from injury and interference with the performance of their normal function, which would result from being subjected to any crushing strains. The latticed front wall of the stationary crushing member, constitutes its crushing face, which the feeder chains can never approach sufficiently to be subjected to strain or impairment of their free movements, and, in their passage through the longitudinal slots of the stationary crushing member, they permit the smaller

particles of coal to pass along the slots and drop into the conveyor casing, and push only the lumps into the crushing zone.

I claim as my invention and desire to secure by Letters Patent:

1. In a mechanical stoker, the combination of a traversing feeding mechanism for advancing all of the fuel; a stationary crushing member, operative at a point beyond the adjacent terminal of the traverse of said feeding mechanism, in position to receive coal therefrom and separated from said terminal to permit the discharge of fine coal; a movable crushing member, oscillatable towards and from the stationary crushing member; and a delivery mechanism for conveying coal from the feeding mechanism and the crushing mechanism to a steam boiler firebox.

2. In a mechanical stoker, the combination of a traversing feeding mechanism; a stationary crushing member, operative at a point beyond the adjacent terminal of the traverse thereof, in position to receive coarse coal therefrom, in advance of its working face and permit the discharge of fine coal to the rear of said member; a movable crushing member, oscillatable towards and from the stationary crushing member, and a delivery mechanism for conveying coal from the feeding mechanism and the crushing mechanism to a steam boiler firebox.

3. In a mechanical stoker, the combination of a traversing endless drag chain fuel feeder; a stationary crushing member, operative at a point beyond the adjacent terminal of the traverse thereof, in position to receive coal therefrom, and slotted at top for the traverse of the drag chain and the discharge of particles of coal not requiring crushing; a movable crushing member, oscillatable towards and from the stationary crushing member; and a delivery mechanism for conveying coal from the crushing mechanism to a steam boiler firebox.

4. In a mechanical stoker, the combination of a traversing feeding mechanism; a stationary crushing member, operative at a point beyond the adjacent terminal of the traverse thereof, said crusher member being provided with coal delivery passages, located between the feeding mechanism and its operative face; a movable crusher member, oscillatable towards and from the stationary crusher member; and a delivery mechanism for conveying coal from the crushing mechanism to a steam boiler firebox.

5. In a mechanical stoker, the combination of a traversing feeding mechanism including a trough and a plurality of endless drag chains operating therein, a stationary crushing member operative at a point beyond the termini of the traverse of said drag chains on coarse fuel conveyed thereby and provided with passages adjacent said termini

- to permit the discharge of fine fuel, a movable crusher member oscillatable toward and from the stationary crusher member, and a delivery mechanism for conveying all of the fuel to a steam boiler furnace.
6. In a mechanical stoker, the combination of a traversing feeding mechanism; a crushing mechanism, operative at a point beyond the adjacent terminal of the traverse of the feeding mechanism, and comprising spaced apart stationary and movable crushers, adapted to permit the discharge of fine coal between the feeding mechanism and the stationary member, and the deposit of large coal between the stationary and the movable members; and a delivery mechanism for conveying all of the coal to a steam boiler firebox.
7. In a mechanical stoker, a stationary crusher member, comprising a longitudinally slotted upper plate, and a depending face portion in which are formed a plurality of slots.
8. In combination, a bin having a flat bot-
- tom, a crusher positioned to receive material from the bin, mechanism for advancing material to the crusher, and a riddle located between the crusher and the zone of action of the advancing means and over which the material is pushed.
9. In combination, a bin having a flat bottom and a discharge opening at its bottom, mechanism for advancing material to such opening, and a riddle partially crossing the opening from the side thereof to which the fuel is advanced.
10. In combination, a fuel bin having a discharge opening at its bottom, a conveyor receiving from the opening for delivering to a furnace, endless drag chains crossing the bottom of the bin and delivering to the opening, a crusher interposed between the opening and the conveyor and provided with openings for the passage of fine fuel to the conveyor without subjecting it to crushing action.

ADAM B. FAHNESTOCK.
